UNITED STATES PATENT OFFICE.

ALBERT L. HARVEY, OF WILKINSBURG, PENNSYLVANIA, ASSIGNOR TO WESTINGHOUSE ELECTRIC & MANUFACTURING COMPANY, A CORPORATION OF PENNSYLVANIA.

CONTROL SYSTEM.

1,412,522.

Specification of Letters Patent. Patented Apr. 11, 1922.

Application filed May 7, 1919. Serial No. 295,290.

To all whom it may concern:

Be it known that I, ALBERT L. HARVEY, a citizen of the United States, and a resident of Wilkinsburg, in the county of Allegheny and State of Pennsylvania, have invented a new and useful Improvement in Control Systems, of which the following is a specification.

My invention relates to motor-control systems and particularly to systems for controlling intermittently operated motors.

In intermittently operated compound or shunt-wound motors, provision must be made for disconnecting the shunt field-magnet winding from the source of energy when the motor is at rest to prevent overheating and burning out of the winding. If the motor is designed for dynamic-braking, however, the winding must be maintained energized until the motor has come substantially to rest.

The object of my invention is to provide an improved motor-control system for shunt or compound-wound motors which shall insure the de-energization of the shunt field-magnet winding when the motor is at rest but the energization thereof during running and dynamic braking.

According to my invention, the shunt field-magnet winding is adapted to be energized by a relay having two coils, one of which is connected across the starting resistor and the other across the armature brushes. The first-named coil effects the closing of the relay and the second maintains it closed until the motor has come practically to rest.

In the accompanying drawing, which is a diagrammatic view of circuits and apparatus embodying my invention, a compound-wound motor, having an armature 1, a series field-magnet winding 2 and a shunt field-magnet winding 3, is connected to line conductors 4 and 5, which, in turn, are connected to any suitable source of direct current. A controller 6, which is here shown as of the drum type, is adapted to connect the armature to the line conductors 4 and 5 and to effect the short-circuiting of an accelerating resistor 7, which is in series with the armature 1. The shunt field-magnet winding 3 is normally disconnected from the line conductors 4 and 5 but is adapted to be connected thereto by a relay 8 having an energizing

winding 9, that is connected across a starting resistor 7, and a second winding 10 that is connected across the armature 1.

Assuming the controller 6 to be actuated, for example, to the right, a circuit will be established from the line conductor 4, through stationary contact members 11 and 12, which are bridged by the drum controller 6, the series field-magnet winding 2, the armature 1 and a stationary contact member 13 of the controller 6, by a conductor 14, through the resistor 7, a stationary contact member 15 of the drum controller 6, which, in the first position to the right of the drum controller 6, is in engagement with a movable contact member 16 and, through segment 17 and stationary contact member 18, to the line conductor 5. The armature 1 is thus connected to the line conductors 4 and 5 in series with the field-magnet winding 2 and the starting resistor 7.

The closing of this circuit results in a flow of current through the resistor 7 so that the coil 9 becomes energized in accordance with the drop in voltage across this resistor. The relay 8 becomes thereupon closed to connect the shunt field-magnet winding 3 to the line conductors 4 and 5.

Further actuation of the controller 6 to the right will effect the short-circuiting of successive portions of the resistor 7 until, ultimately, the resistor becomes entirely short-circuited. The coil 9 becomes thereby de-energized, but the relay 8 is maintained in actuated position, to maintain the connection of the field-magnet winding 3 to the line conductors 4 and 5, by the coil 10, which is energized in accordance with the counter-electromotive force of the motor.

To stop the motor, the controller may be actuated to the left, until it occupies the illustrated, "off" position, whereupon a circuit is established from one brush of the armature 1, through contact members 13 and 19 and a dynamic-braking resistor 20, to the other brush of the armature 1. The motor may thus be dynamically-braked. During such braking, the coil 10 is maintained energized, in accordance with the counter-electromotive force of the motor, so that the field-magnet winding 3 is maintained energized until the motor comes substantially to rest, at which time the relay will become open by

gravity to disconnect the winding 3 from the line conductors 4 and 5 and thereby protect the winding 3 from possible injury from overheating while the motor is at rest.

5. The motor may be operated in the opposite direction by actuating the controller 6 to the left.

In accordance with my invention, the shunt field-magnet winding of a motor is disconnected from the source of energy whenever the motor is at rest but is connected thereto during normal operation and during dynamic-braking. Obviously, my invention is not restricted to the specific details above illustrated and described and I desire, therefore, that the appended claims shall be construed broadly, except in so far as limitations may be specifically imposed therein.

I claim as my invention:

20. 1. The combination with an electric motor having an armature and a field-magnet winding and a starting resistor in circuit with said motor, of means controlled in accordance with the drop in potential across said resistor

and across said armature for controlling said winding. 25

2. The combination with an electric motor having an armature and a shunt field-magnet winding and a starting resistor in circuit with said motor, of means controlled by the current traversing said armature and the drop in potential across said resistor for closing the circuit of said winding. 30

3. The combination with an electric motor having an armature and a shunt field-magnet winding, and a starting resistor in series with said motor, of a switch for closing the circuit of said winding having energizing coils connected across said resistor and said armature. 35

4. The combination with an electric motor having an armature, and a shunt field-magnet winding, of a switch for closing the circuit of said winding having an energizing coil connected across said armature. 40

In testimony whereof, I have hereunto subscribed my name this 23d day of April 1919. 45

ALBERT L. HARVEY.
